(57) **CLAIM**

The ornamental design for a face pigment applicator, as shown and described.

DESCRIPTION

Related applications include:

U.S. Utility patent application Ser. No. 12/381,596

U.S. Utility patent application Ser. No. 12/381,630

FIG. 1 is a perspective view of the left face pigment applicator, showing my new design;

FIG. 2 is a front elevational view;

FIG. 3 is a rear elevational view;

FIG. 4 is a top plan view;

FIG. 5 is a bottom plan view;

FIG. 6 is a left side elevational view;

FIG. 7 is a right side elevational view.

FIG. 8 is a perspective view of a second embodiment of the right face pigment applicator which is a minor image of the left face pigment applicator;

FIG. 9 is a front elevational view;

FIG. 10 is a rear elevational view;

FIG. 11 is a top plan view;

FIG. 12 is a bottom plan view;

FIG. 13 is a left side elevational view; and,

FIG. 14 is a right side elevational view.

The broken lines in the drawing are for illustrative purposes only and form no part of the claimed design.
